US0D1052732S

(12) **United States Design Patent** (10) **Patent No.:** **US D1,052,732 S**
(45) **Date of Patent:** **** Nov. 26, 2024**

(54) **SUBTALAR WEDGE**

(71) Applicant: **RESTOR3D, INC.**, Durham, NC (US)

(72) Inventors: **Michaela Pigue**, Durham, NC (US);
Nathan Timothy Evans, Durham, NC (US); **Chris Kreulen**, Sacramento, CA (US)

(73) Assignee: **RESTOR3D, INC.**, Durham, NC (US)

(**) Term: **15 Years**

(21) Appl. No.: **29/876,664**

(22) Filed: **May 25, 2023**

(51) **LOC (14) Cl.** **24-03**

(52) **U.S. Cl.**

USPC **D24/155**

(58) **Field of Classification Search**

USPC D24/155

CPC A61F 2/4611; A61F 2/442; A61F 2/447

(57) **CLAIM**

The ornamental design for a subtalar wedge as shown and described.

DESCRIPTION

FIG. 1 is a perspective view of a subtalar wedge, according to one embodiment of the present disclosure;

FIG. 2 is a perspective view of a subtalar wedge, according to one embodiment of the present disclosure;

FIG. 3 is a back view of a subtalar wedge, according to one embodiment of the present disclosure;

FIG. 4 is a front view of a subtalar wedge, according to one embodiment of the present disclosure;

FIG. 5 is a side view of a subtalar wedge, according to one embodiment of the present disclosure;

FIG. 6 is a side view of a subtalar wedge, according to one embodiment of the present disclosure;

FIG. 7 is a side view of a subtalar wedge, according to one embodiment of the present disclosure; and,

FIG. 8 is a side view of a subtalar wedge, according to one embodiment of the present disclosure.

The broken lines form no part of the claimed design and illustrate portions of the subtalar wedge.

1 Claim, 8 Drawing Sheets
